To all whom it may concern:

Be it known that I, Edwin C. Meyers, a citizen of the United States of America and resident of Syracuse in the county of Onondaga and State of New York, have invented a new, original, and ornamental Design for a Combined Display and Self-Service Candle Bar, of which the following is a specification, reference being had to the accompanying drawings forming part thereof:

In the drawings:

Figure 1 is a front elevational view of a combined display and self-service candle bar, showing my new design;

Figure 2 is a side elevational view thereof;

Figure 3 is a sectional view on the line 3—3 of Figure 1;

Figure 4 is a top plan view;

Figure 5 is a fragmentary sectional view on the line 5—5 of Figure 1; and

Figure 6 is a sectional view on the line 6—6 of Figure 1.

I claim:

The ornamental design for a combined display and self-service candle bar, substantially as shown.
